Primary Examiner — Shawn T Gingrich

(57) **CLAIM**

The ornamental design for optical fiber connector, as shown and described.

DESCRIPTION

1. Optical fiber connector

1.1 : Perspective

1.2 : Front

1.3 : Back

1.4 : Top

1.5 : Bottom

1.6 : Left

1.7 : Right

1.8 : Reference view

The broken line portion of the reproductions is included to show portions of the optical fiber connector that form no part of the claimed design.

1 Claim, 8 Drawing Sheets(56)
